UNITED STATES PATENT OFFICE.

JAMES H. BARNES, OF MONTGOMERY, NEAR DAYTON, OHIO.

METHOD OF AND MEANS FOR GENERATING THE INVOLUTE PROFILES OF GEAR TEETH.

Application filed August 27, 1923. Serial No. 659,564.

It is the principal object of my invention to provide a simple, accurate and economical method of, and means for, generating the profiles of the teeth of gears and similar 5 elements after said teeth have been roughed out.

The means which I provide for generating the involute working surface or profiles of gear teeth and like elements, is a rolling 10 curve shaving cutter whose cutting action is in the direction of the roll of the gear teeth as distinguished from other cutters of the rotary, rack, pinion and hob type whose cutting action is at right angles to the direction 15 of the roll of the gear teeth. Gear teeth which are cut in the previously known manner, as by a rack or by a hob, necessarily have minute ridges extending transversely across the working surfaces of the gears, and 20 as these ridges roll and slide together when two or more of these gears are intermeshed, the result is a noise and an excess of friction which is overcome by shaping the teeth in the manner to be herein described in which 25 the shave of the finishing cut is taken from the end of the tooth inwardly toward the root of the tooth or in the direction of the involute. In involute teeth the direction of 30 the involute is the direction of roll of the teeth. The finishing cut is preferably made in a single operation by having the width of the cutter of substantially the same extent as the full width of the gear.

Among the advantages which I claim for 35 my method of cutting gears is accuracy of product, speed of production, interchangeability and reduction of noise of operation of the gear that is cut.

Other important and incidental objects 40 will be brought out in the following specification and particularly set forth in the subjoined claims.

In the accompanying drawings illustrating 45 my invention, Figure 1 is a diagrammatic view showing the generation of an involute line. Figure 2 is a diagrammatic view showing the generation of an involute surface. Figure 3 is a diagrammatic view 50 showing how the generation of an involute surface is adapted to my method of generating the involute profiles of gear teeth. Figure 4 is a side elevational view of a device which may be employed for carrying my method of cutting gears into effect. Fig-

ure 5 is an end elevational view of that device. 55 Figure 6 is a plan view thereof. Figure 7 is a side elevational view of said device, in section. Figure 8 is an end elevation of the same, partly in section. Figure 9 is an end elevation of the cutting portion of the device, 60 showing the blade before cutting. And Figure 10 is an end elevation of the cutting portion of the device, showing the blade advanced well into the cut.

Throughout the specification and drawings, similar reference characters denote 65 corresponding parts.

For the purpose of quickly and accurately generating the involute profiles of spur gear teeth, I preferably employ a plane tool 70 identical with the generating plane illustrated in Figure 3, for the following reasons.

If a taut string is wound around a cylinder and then unwound, the free end of the string will describe an involute line, and the string will always be tangent to the periphery of the cylinder. For example, in Figure 1 c represents the cylinder, and p , p_1 and p_2 designate successive positions of the 75 free end of the taut string, describing the involute line i . t_1 represents the length of the string or tangent for the position p_1 , and t_2 for the position p_2 . Thus the involute line i is described by a point in a tangent identical with the string, rolling on the periphery of the cylinder, the length of 80 the tangent increasing as the unwinding proceeds.

In Figure 2, p_1 and p_2 and $p_{1.1}$ and $p_{2.2}$ are describing points for involutes i and i_1 . l_1 and l_2 , which connect p_1 to $p_{1.1}$ and p_2 to $p_{2.2}$ respectively, designate two positions 85 of the line which generates the involute surface s .

If, as in Figure 3, there is provided a tool m having a cutting edge n that corresponds with the generating line l_1 in Figure 2, in a plane e at approximately right angles to the rolling tangent t_1 , then the edge n in the tangent plane t , is the generating line for 100 the involute surface s .

A hand power device that operates on the above described principle for finishing the involute surfaces of spur gears, will now 105 be described in connection with Figures 4 to 10 of the drawings. This device consists primarily of a base or support 1, which

preferably consists of a casting having two upright arms 2, 2 containing holes in their upper ends into which are pressed the reduced ends of two base cylinders 3, 3 corresponding to the cylinder *c* in Figures 1, 2 and 3. Each base cylinder 3 forms a bearing for a sleeve which extends from the outside surface of the upright member to the face of the roughed gear blank to be cut, the right sleeve, the roughed gear and the left sleeve being designated by the numerals 4, 5 and 6 respectively. (See Figures 4 and 7.)

The inner end of the sleeve 6 is drilled and tapped to provide a hole 7 into which the inner threaded end of a spindle 8 is screwed after the latter has been passed through the bore of the gear and the sleeve 4. (See Figure 7.) Placed on the outer end of the spindle is a thrust washer 9 which is forced against the outer end of the sleeve 4 by the hexagon head 10 of the spindle.

The sleeve 6 has an outer reduced end 11 which is drilled and tapped to receive a screw 12 which passes through a thrust washer 13 that engages the outer face of an index wheel 14 keyed on the reduced end 11 of the sleeve, to press it firmly against the shoulder face of the latter. (See Figure 7.)

Near its outer edge the index wheel 14 contains a series of radial holes 15 corresponding in number to the number of teeth on the gear 5 to be cut. Provided in the left upright member 2 below the axis of the gear 5, is a hole 16 to receive a removable index pin 17 after the latter has been passed through one of the radial holes 15 in the index wheel 14. (See Figures 7 and 8.) The sleeves 4 and 6, which are mounted in the support 1, together with the associated spindle 8, form a means for holding a gear or a gear blank in position, and the base members 3—3 form master surfaces of curved contour about which the tool holder is constrained to oscillate.

Adapted to rock or roll upon the cylindrical base members 3, 3 is a tool holder 18 now to be described. The latter preferably consists of a casting which has two side wing portions that are integrally connected to a raised central body portion of U section to provide the necessary clearance for the outer portion of the gear 5. (See Figure 7.) The body portion of the tool holder has two downwardly projecting thrust flanges 19, 19 which engage the inner ends of the base cylinders 3, 3 to prevent any side twist of the tool holder.

To maintain at all times the proper contact between the lower surfaces of the wing portions of the tool holder 18 and the peripheries of the base cylinders 3, 3, the following means are provided. Secured in parallelism to the under surface of each wing portion of the tool holder, is a pair of

bands 20, 20. Each pair of these bands is so secured to its respective wing portion, near the outer end thereof, that their opposite ends will be free for attachment to the periphery of the base cylinder so that said wing portion may freely roll upon the latter without sliding. Figs. 4 and 5 show the tool holder in a central position, while Figs. 7 and 8 show the tool holder in positions where the cut has not been started, and with the blade advanced well into the cut respectively. This rolling or rocking movement of the tool holder is effected by an oscillating bracket 21 of U section, having two arms 22, 22 that are pivotally secured to reduced portions of the base cylinders 3, 3. Secured between the upper portions of the arms 22, 22 of this bracket is a transverse shaft 23 upon the middle portion of which there is loosely mounted between two collars 24, 24, a roller 25 which engages the top surface of the body portion of the tool holder 18. The roller 25 thus provides a roller means operably connected to the main support 1 to exert a downward force on the tool holder so as to assist the bands 20 in taking the strain which results when a cut is being taken by the tool 27. Pressed into a hole in the top portion of the bracket 21 is a handle 26 by means of which the bracket is oscillated to impart a rolling motion to the tool holder and to the tool now to be described, which it carries.

To receive this tool, which will be designated by the numeral 27, a recess is cut in the body portion of the tool holder, and in this recess the tool is firmly held by screws 28, 28 which enter tapped holes 29, 29 in said body portion. (See Figures 4, 7 and 8.) The tool 27 is thus held by the tool holder 18 in right relationship to the gear 5 to be cut.

In operation, the oscillating bracket 21 is moved by its handle 26 to its initial cutting position on a tooth of the gear 5, which is held stationary between the sleeves 4 and 6 when the latter sleeve is locked by the index pin 17 by virtue of its passage through the radial hole 15 for that position in the index wheel 14, into the locking hole 16 in the base member 1. The gear now being locked in a stationary position, the bracket 21 is oscillated by its handle 26 to cause the tool 27 to generate the involute working surface or profile of one side of the tooth; and when the position of the gear is reversed, the involute profile of the other side of the tooth may be generated in the same manner. (See Figures 4 and 8.)

It will now be seen that the movement of the tool 17 by the oscillating bracket 21, in generating the involute profile of one side of a gear tooth, will exactly follow the movement of the edge *n* in Figure 3 when generating the involute surface *s*. To the

cylinder *c* in the latter figure, correspond the base cylinders 3, 3 on which roll the lower wing surfaces of the tool holder 18 that correspond to the tangents t_1 in said figure. The bands 20 which maintain the proper contact between those wing surfaces and the base cylinders, may be each likened to the taut string in Figure 1. This comparison being established, it follows that my method and means for generating the involute profiles of gear teeth will result, among other things, in accuracy and speed of production as well as in the reduction of the noise of operation of the gears that are cut.

The device which I have described for cutting the gears may be modified if desired, and may be driven by any motive power other than that derived from the hand. Furthermore, while I have shown but one tool in the device illustrated in the drawings, these tools may be in multiple.

Having described my invention, I claim:

1. The herein described method of finishing the curved non-circular working surfaces of a rolling power transmitting body which consists in causing a tool to shave the working surfaces of the body so that a continuous cut is taken for substantially the entire length of said working surface in the direction of roll of said surface.

2. The herein described method of finishing a curved working surface of the teeth of a toothed power transmitting body which consists in causing a tool to take a continuous shave on a working surface of the teeth in the direction of roll of the teeth.

3. The method of cutting an involute working surface on a blank which consists in cutting the working surface so that a continuous cut of a substantial length is made in the direction of the involute to cut every point in the working surface in the direction of the involute.

4. The method of finishing the curved working surfaces of gear teeth, which consists in causing a wedge shaped shaving tool to successively shave the working surfaces of the teeth so that continuous shaves are made of substantial lengths on each working surface in the direction of roll of the working surfaces.

5. The method of finishing a substantially involute working surface of a gear tooth which consists in shaving the working surface of the tooth from the end inwardly to the root of the tooth in a single cut.

6. The herein described method of cutting the curved working surfaces of gear teeth which consists in shaving the working surfaces of said teeth so that continuous shaves are taken in the direction of roll of the teeth.

7. The method of finishing an involute working surface of an involute spur gear which consists in causing a straight edged

shaving tool to shave the working surface so that a single continuous shave is taken from the end inwardly to the root of a tooth.

8. The method of making substantially involute gear teeth consisting in making a roughed gear blank and subsequently shaving the working surfaces of the teeth so that a single continuous shave is made for the full length of each working surface in the direction of roll of said surface.

9. A toothed member having gear teeth with power transmitting surfaces finished by a continuous shave for the full length of each surface, made in the direction of roll of said surface said surface being perfectly smooth along lines in the direction of roll of said surface.

10. A member having an involute surface of a substantial length finished by a single continuous cut made in the direction of the involute, every point in said surface being cut in the direction of the involute.

11. A gear having involute working surfaces finished by shaving each surface by a single continuous shave made for the full length of said working surface from the end inwardly to the root of the tooth said surface being perfectly smooth along lines in the direction of the involute.

12. A gear having gear teeth with curved working surfaces each finished by a continuous shave taken in the direction of roll of said surface said surface being perfectly smooth along lines in the direction of roll of said surface.

13. A gear having gear teeth with substantially involute working surfaces which are perfectly smooth along substantially involute lines, made by shaving each surface substantially in the direction of roll of the surface by a single continuous shave.

14. A spur gear having gear teeth with substantially involute working surfaces which are perfectly smooth along substantially involute lines, finished by shaving each surface for the full width thereof by a single continuous shave made for the full length of said working surface from the end inwardly to the root of the tooth.

15. In a device of the class described, a support, means mounted in said support for holding a roughed blank to be provided with finished power transmitting surfaces, a tool holder movably mounted adjacent to said blank, a tool therefor, and means for moving said tool holder so that the tool takes a continuous shave on the blank substantially in the direction of roll of said surface.

16. In a device of the class described, a support, means mounted in said support for holding a gear fixed in position while being cut, a tool holder movably mounted on said means, a tool therefor, and means for mov-

ing said tool holder so that the tool takes a tooth of said gear in the direction of roll of shave in the direction of roll of a tooth of said gear to cut a working surface on said tooth.

- 5 17. In a device of the class described, in combination, a support, means mounted in said support for holding a gear, a tool holder movably mounted adjacent to said gear, an edged tool fixed in said holder, and 70 means for moving said tool holder so that the edge of the tool moves along a substantially involute path so as to shave the working surfaces of the teeth from the ends inwardly to the roots thereof.
- 13 18. In a device of the class described, in combination, a support, means mounted in said support for holding a gear in fixed position while being cut, a tool holder movably mounted adjacent to said gear, a straight 75 edged tool of substantially the same width as the gear mounted in said tool holder, and means for moving said tool holder so that the straight edge of the tool describes an involute curved surface in space so as to shave a working surface of the tooth from the end inwardly towards the root thereof in a single operation.
- 15 19. In a device of the class described, a support, means for holding a roughed gear 80 in said support, means for indexing said gear, a tool holder movably mounted in said support, a tool fixed in said tool holder, means for moving said tool holder so that the tool takes a shave on a working surface 85 of a tooth of said gear in the direction of roll of the tooth and a roller cooperating with said tool holder to take a portion of the strain on said holder when a shave is made and to transmit said strain to said support.
- 20 20. In a device of the class described, in combination, a support, means for holding a gear, a tool holder movably mounted adjacent to said gear, a straight edged tool 90 movably mounted therein, means for oscillating said tool holder back and forth along a predetermined path so that every point in the edge of the tool travels along substantially involute paths to describe a substantially involute working surface on said gear, and a roller cooperating with said tool holder to transmit a portion of the strain on said holder, when the shave is made to said support.
- 25 21. In a device of the class described, in combination, a support, means mounted in said support for holding a gear, a device for moving said means a predetermined amount for indexing said gear, a tool holder movably mounted on said means adjacent to said gear, a straight edged tool removably held therein, a roller cooperating with said tool holder and said support for moving said tool holder so that the cutting edge of the tool 100 shaves an involute working surface on a 95
22. In a device of the class described, the combination with a support, of means for holding a gear in a stationary position to the latter, a tool holder oscillatably mounted on said support adjacent to said gear, a tool carried by said holder having a substantially straight cutting edge and mounted in fixed position in relation to said holder while a cut is being made, a cylinder, tension elements interconnecting said cylinder and said tool holder to restrain said tool holder to roll on the surface of said cylinder, and means for moving said holder so that it oscillates over the surface of said cylinder to describe an involute surface on said gear, for each oscillation.
23. In a device of the class described, in combination, a support, gear holding means mounted in said support, a tool holding means mounted on said support, a tool therefor, and mechanism for relatively moving said two means so that the tool takes a continuous shave on the working surface of a tooth on said gear in the direction of roll of said surface and for the full length of said surface.
24. In a device of the class described, in combination, a support, gear holding means mounted in said support, a tool holding means mounted on said support, a tool therefor, and mechanism for relatively moving said two means so that the tool takes a single continuous shave along a substantially involute path so as to continuously shave each working surface of the teeth from the ends inwardly to the roots thereof.
25. In a machine for cutting involute surfaces in the direction of roll of the involute, in combination, a support, blank holding means for holding a blank to be provided with an involute surface, a cutter, means for holding said cutter, a device for maintaining one of said means stationary on said support while a cut is being made on said blank, and mechanism for moving said other means on said support so that said cutter cuts an involute surface on said blank of a substantial length, said cut being made in the direction of roll of the involute surface.
26. A machine for cutting involute surfaces in the direction of roll of the involute, comprising, in combination, a support, blank holding means on said support for stationary holding a blank to be provided with an involute surface, a cutter, a cutter holding means movably mounted on said support, and means for moving said cutter holding means so that said cutter moves along an involute path in space to cut an involute surface of substantial extent on said blank so that the cut is made in the direction of roll of the involute surface.

27. A machine for cutting involute surfaces in the direction of roll of the involute, comprising, in combination, a support, blank holding means on said support for 5 stationarily holding a blank to be provided with an involute surface, a cutter, a cutter holding means movably mounted on said support, and means for moving said cutter holding means so that said cutter moves 10 along an involute path in space to cut an involute surface of substantial extent on said blank so that the cut is made in the direction of roll of the involute surface, said last named means comprising a master surface 15 and means for restraining said tool holder to roll on said master surface so that a line on said tool holder rolls on a base circle line of said master surface in conjunctive relation.
- 20 28. In a gear cutting machine, in combination, a support, means for holding a roughed gear blank fixed in position on said support while a cut is being made, tool holding means oscillatably mounted adjacent to 25 said gear, a straight edged shaving tool mounted in said tool holder and fixed therein while a cut is being made, a curved master surface fixed to said support, having a constant distance across the same, said 30 master surface oscillatably supporting said tool holder thereon, means controlling the movement of said tool holder on said master surface to cause the edge of the tool to describe a substantially involute surface, and 35 means for moving said tool holder to cause the edge of said tool to shave a substantially involute working surface on said gear blank so that each shave is continuous and made substantially in the direction of roll 40 of said surface, and means for indexing said gear blank and gear blank holding means between cuts.
29. In a device of the class described, in combination, a support, means for holding a 45 roughed gear in said support, a tool holding means mounted in said support adjacent to said gear, a tool mounted in said tool holding means having a wedge shaped operating edge of substantially the same width as said gear, a device for relatively indexing 50 said two means, and mechanism for relatively moving said two means so that the tool takes a shave on the working surface on the tooth of said gear in the direction of roll of said surface.
30. In a device of the class described, in combination, a support, means mounted in said support for holding a roughed gear, tool holding means mounted in said support 55 adjacent to said gear, a straight edged tool removably held in said tool holding means, a device for indexing said gear in relation to said tool holding means, and mechanism including a roller cooperating with one of 60 said means and said support for relatively moving said two means so that the cutting edge of the tool takes a shave on the working surface of the tooth of said gear from the end inwardly to the root thereof.
31. In a device of the class described, in combination with a support, means for holding a roughed gear blank in said support, tool holding means mounted in said support adapted to hold a tool, a cylinder, mechanism operably interconnecting said cylinder and said tool holding means so that they are constrained to relatively oscillate one on the other and comprising a roller oscillatable about the axis of the gear and 70 interconnecting the tool holder and the support for governing the movements of the tool holder and transmitting strain on said tool holder to said support, means for producing such relative oscillation, the axes of the cylinder and of the gear blank being alined 75 so that said tool cuts a working surface on the teeth of said gear blank in the direction of roll of said surface.
32. In a device of the class described, in combination with a support, means for holding a roughed gear blank in said support, tool holding means mounted in said support, a straight edged tool in said tool holding means, a cylinder, mechanism operably interconnecting said cylinder and said tool holding means so that they are constrained to oscillate one on the other in conjugate 80 relation, and means for producing such relative oscillation, the axes of the cylinder and of the gear blank being alined so that said tool cuts an involute working surface on the teeth of said gear blank in the direction of roll of said surface.
33. In a device of the class described, in combination with a support, means for holding a roughed gear blank in said support, tool holding means mounted in said support, a tool in said tool holding means, a curved master surface, mechanism operably interconnecting said master surface and said tool holding means so that they are constrained to relatively oscillate one on the other and comprising a roller oscillatable about the axis of the gear and interconnecting the tool holder and the support for governing 90 the movements of the tool holder and transmitting strain on said tool holder to said support, means for producing such relative oscillation, the axes of the master surface and of the gear blank being alined so that said tool cuts an involute working surface on the teeth of said gear blank in the direction of roll of said surface.
34. In a device of the class described, in combination, a support, means for holding a roughed gear blank in said support, tool holding means in said support, a wedge shaped tool in said tool holding means, a master surface having a curved contour and having an axis fixed in said support, mecha- 100 105 110 115 120 125 130

nism operably interconnecting said master surface and said tool holding means so that they are constrained to oscillate one on the other, and means for producing such oscillation, the axes of the master surface and of the gear blank being coincident so that said tool cuts a substantially involute working surface on the teeth of said gear blank in the direction of roll of the said working surface.

35. In a device of the class described, in combination, a support, means for holding a roughed gear blank in said support, tool holding means in said support, a straight edged tool in said tool holding means, a master surface having a generally curved contour fixed in said support, mechanism operably interconnecting said master surface and said tool holding means so that they are constrained to oscillate one on the other, and means for producing such oscillation, said mechanism and said last named means including a roller operably interconnected with said tool holding means, the axes of the master surface and of the gear blank being coincident so that the tool holding means is constrained to oscillate about said generally curved master surface in a curved path, so that said tool cuts a working surface on the teeth of said gear blank in the direction of roll of the said working surface.

36. In a device of the type described, the combination with a support, of means for holding a gear in a stationary position in the latter, a tool holder oscillatably mounted in said support over the gear, a tool carried by said holder, a cylinder, taut elements wound thereon and means for moving said holder to cause the tool to engage the involute portion of a tooth of said gear in a surface generated by a line connecting the

free ends of the taut elements when the latter are wound or unwound from the periphery of the cylinder.

37. In a device of the type described, the combination with a base having two upstanding arms, of two cylinders projecting toward each other from the upper ends of said arms, a sleeve rotatable in each cylinder, a spindle passing through one sleeve into the other sleeve, a gear mounted on said spindle between the sleeves, a tool holder free to oscillate about the axes of the cylinders, bands connected at their opposite ends to the holder and cylinders so that said holder may freely roll on the latter and still be maintained in contact with them, a tool carried by said holder to engage the involute portion of a tooth of said gear, and means for oscillating the tool holder for the purpose specified.

38. In a device of the type described, the combination with a base support, of a pair of base cylinders fixedly secured within said support, a sleeve rotatable in each cylinder, a spindle passing through one sleeve into the other sleeve, a gear mounted on the spindle for tight engagement by the inner ends of said sleeves, a tool holder oscillatable over the peripheries of said cylinders above the gear, a tool carried by said holder to engage the involute surface of the latter, indexing means secured to one of said sleeves to turn the gear to present successive teeth thereon to said tool, and means for locking the indexing means in a stationary position after a gear tooth has been brought into proper position for engagement by the tool.

In testimony whereof I have hereunto set my hand this 25th day of August, 1923.

JAMES H. BARNES.
